E. P. PARSONS

NECKWEAR

Filed April 12, 1926

By Fisher Norton & Wood

Attorney

UNITED STATES PATENT OFFICE.

ERNEST P. PARSONS, OF CLEVELAND, OHIO; W. M. BALDWIN ADMINISTRATOR OF SAID ERNEST P. PARSONS, DECEASED, ASSIGNOR TO THE PARSONS & PARSONS COMPANY, OF CLEVELAND, OHIO.

NECKWEAR.

Application filed April 12, 1926. Serial No. 101,275.

My invention pertains to neckwear, and more particularly to collars made of celluloid or a composition of matter which may be made to resemble a laundered woven fabric. For example, the celluloid or composition of matter which I may use in making the present collar has an inherent stiffness which permits the collar to be worn repeatedly without losing its shape or affecting its appearance under extremes of temperature. The material is flexible but not as flexible as a woven fabric, and it cannot be folded abruptly in its cold finished state without marring or cracking the surface. My present object, therefore, is to construct a collar of such materials in a particular way so as to enhance its life under stress and use, and also to enable a person to button and unbutton the collar with facility and without undue wear or tear at the button-hole tabs and their points of union with the body of the collar. A further object is embodied in the specific arrangement for locking the tabs in proper alignment and position on the collar band.

In the accompanying drawings, Fig. 1 is a perspective view of a collar embodying my invention; Fig. 2, an enlarged cross-section on line 2—2 of Fig. 3, showing the locking connections for the tab; Fig. 3, an enlarged view of the inner side of one tab end of the collar; Fig. 4, a horizontal section of said tab on line 4—4 of Fig. 3; and Figs. 5 and 6, are detail views of the collar and tab, separated. Figs. 7 and 8, are side and edge views, respectively, of the flexible locking and aligning piece for the tab.

The collar shown in the foregoing views comprises a band 2 and an outer fold 3 of the same length, the edge extremities 4 being substantially parallel although not necessarily parallel. As a rule, the outer fold 3 is wider than band 2, especially at the points or meeting ends on the collar, the shape of which may be modified or changed, as desired. Band 2 is provided with a pair of slots 5 at or near each extremity or end edge 4. Slots 5 extend lengthwise of the collar, as shown. They are parallel with the upper fold line 6, and these slots are relatively short and narrow and serve to permit separate tabs 7 having button-holes 8, to be attached to band 2 in a definite fixed position at the opposite ends of the collar. Tabs 7 extend a substan-

tial distance beyond edge 4 and provide 55 freely flexible extensions for the band when the tabs are attached thereto by means of separate flat locking strips 9 of flexible material, preferably the same celluloid material composing the body of the collar and 60 tabs. Thus, each tab 7 has a pair of parallel slots 10—10 at or near one end thereof, which may be placed in register with slots 5 when the tab is inserted between band 2 and fold 3 of the collar. A locking strip 9 is then inserted 65 through one pair of registering slots and thence out of the other pair of registering slots, and the extremities of the locking strip are then bent back flat-wise upon band 2 if the locking strip was first inserted from 70 that side; or it may be first inserted from the other or inner side of the band, and be in a reversed position than as shown in Fig. 2. The locking strips fit the slots snugly, and by using two or more parallel slots the tab 75 will be locked quite firmly in a definitely aligned fixed position upon the band. In practice, the meeting faces of the locking strips and the band and tab are cemented 80 together, thus securing the tab more permanently in place upon the band. The locking strips 9 in themselves resist end strains and pull, and of course also prevent the separation of the tab from the band in a lateral direction, but where a permanent union is desired I find it desirable to cement the strips 85 in place, especially the ends of the tab above and below the slots through which the strip projects.

What I claim is:

1. A collar of celluloid or similar material having a slotted neck band, button-hole tabs having slots adapted to register into the slots in the band, said tabs being cemented to said band and extending beyond the end edges 95 thereof, and supplemental means uniting said band and tabs together at and by means of said slots, said means being cemented to said tabs.

2. A collar of celluloid material, having a neck band provided with a plurality of slots at each meeting end thereof, button-hole tabs having slots adapted to register with the slots in the band, locking pieces for said parts extending through both sets of said 105 slots, said band and tabs and locking pieces being cemented together.

3. A collar of celluloid or equivalent ma-

terial, having a neck band provided with parallel slots extending lengthwise thereof, button-hole tabs cemented to said band having parallel slots placed in register with the band slots, and narrow flexible locking strips for said tabs having their opposite ends extending through the respective registering slots.

4. A collar of celluloid or similar material having a neck band, separate button-hole tabs overlapping said neck band, and separate locking strips extending through the overlapping portions of said band and tabs, said strips being cemented at their ends to one of the overlapping parts.

5. A collar made of celluloid material, comprising a neck band having a pair of slots in each end portion, separate button-hole

tabs having slots adapted to register with the slots in the band, and locking strips adapted to extend through said slots to secure the tabs to the band, said tabs being partly cemented to the band and the locking strips being cemented to one of said parts.

6. A collar made of celluloid or similar material, having a divided neck band provided with a pair of parallel slots in each end, separate tabs having button-holes and parallel slots, flat locking strips of flexible material extending through said slots to secure the tabs to the band, each tab being cemented to the band and each strip being cemented to both the band and tab.

In testimony whereof I affix my signature.

ERNEST P. PARSONS.
